Primary Examiner — Keli L Hill*Assistant Examiner* — Harold E Blackwell, II(74) *Attorney, Agent, or Firm* — McAndrews, Held & Malloy, Ltd.(57) **CLAIM**

The ornamental design for a fastener insert, as shown and described.

DESCRIPTION

FIG. 1 is a side perspective view of a fastener insert;
 FIG. 2 is a front side elevation view thereof;
 FIG. 3 is a rear side elevation view thereof;
 FIG. 4 is a right side elevation view thereof;
 FIG. 5 is a left side elevation view thereof;
 FIG. 6 is a top plan view thereof; and,
 FIG. 7 is a bottom plan view thereof.

The broken lines in the drawings illustrate portions of the fastener insert that form no part of the claimed design. Further, the appearance of any portion of the fastener insert between the break lines of FIGS. 1 through 5 forms no part of the claimed design.

1 Claim, 7 Drawing Sheets(56)
